United States Patent Office

Des. 185,413
Patented June 9, 1959

185,413

HOUSING FOR MINIATURIZED RADIO

William J. Browner, San Leandro, Calif.

Application December 31, 1957, Serial No. 49,084

Term of patent 14 years

(Cl. D26—14)

Fig. 1.

Fig. 2.

Fig. 3.

Fig. 4.

Fig. 1 is a perspective view of a housing for miniaturized radio, showing my new design with the antenna in extended position;

Fig. 2 is a side elevational view showing the antenna in retracted position, the opposite side being substantially a mirror image thereof;

Fig. 3 is a front end elevational view as viewed from the left in Fig. 2; and

Fig. 4 is a rear elevational view thereof, as viewed from the right in Fig. 2.

I claim:

The ornamental design for a housing for miniaturized radio, as shown and described.
